INVENTOR.
Harry N. Sorenson.
By Clark, Crampton & Crampton,
Atty.

UNITED STATES PATENT OFFICE.

HARRY N. SORENSEN, OF TOLEDO, OHIO.

DOOR HINGE.

Application filed October 24, 1921. Serial No. 509,886.

To all whom it may concern:

Be it known that I, HARRY N. SORENSEN, a citizen of the United States, and a resident of Toledo, county of Lucas, and State of Ohio, have made an invention appertaining to a Door Hinge; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to hinges of the type particularly intended for use in connection with the doors of automobiles.

An object of the invention is the provision of a simple, strong and inexpensive hinge of the character described which is capable of being easily and quickly attached to a vehicle body frame in a novel and highly efficient manner.

A further object of the invention is the provision of a double hinge for carrying two doors on the same side of a vehicle body with the body attaching member of the hinge formed in a single piece serving for the hinge of two doors and adapted to extend from one door opening to another.

A further object of the invention is to simplify and cheapen the hanging of doors in vehicle bodies and to lessen the labor incident thereto.

The invention is fully described in the following specification, and while, in its broader aspect it is capable of embodiment in numerous forms, a preferred embodiment thereof is illustrated in the accompanying drawings, in which,—

Fig. 1 is a fragmentary side elevation of an automobile body equipped with a hinge embodying the invention and with a portion of the body broken away to expose the hinge. Fig. 2 is an enlarged top view of the hinge embodying the invention with one door member of the hinge in closed position and the other door member thereof in partial open position with respect to the body member of the hinge. Fig. 3 is a section on the line 3—3 in Fig. 2, and Fig. 4 is a perspective view of the double body member of the hinge.

Referring to the drawings, 1 designates a

vehicle body having the front and rear doors 55 2 and 3, respectively, closing openings therein and hung at adjacent edges of said opening so that the front door opens rearwardly and the rear door opens forwardly. The frame structure of the vehicle body and over 60 which the outer casing 4 is drawn is provided with the door jambs or parts 5 to which the body members of the hinges are attached.

The body member of the hinge embodying the invention comprises a jamb-plate 6 of sufficient length to span the space between the front and rear door openings, and this plate is provided with screw receiving openings 7 to adapt it to be secured to the body frame between the door openings on the same side of a vehicle and particularly to the door jamb posts 5. The plate 6 has a hooked socket member 8 of U-shape projecting inwardly therefrom adjacent to each end in 70 substantially horizontal position with the lower leg of the member fixedly connected to the plate 6 and with its upper leg terminating short of the plate to provide a space 9 therebetween but being preferably on substantially a plane with the upper edge of the plate as shown. In the present instance the member 8 is integral with the plate 6 being struck and bent inward therefrom and forming the plate with an opening 10 above the 75 lower leg of the member. Each hook member 8 is provided near the inner end of its lower leg with an opening 11. When a jamb-plate 6 is secured to the frame of a vehicle body the hook members 8 thereof project in sockets provided in the jamb posts 5 with the outer ends of their sockets opening to and facing the respective door openings.

Each door member of a hinge comprises 95 a plate 12 adapted to be secured by screws or in any other suitable manner to the inner edge of a door and having an L-arm 13 projecting from the inner edge thereof a distance to adapt the arm to project into 100 the socket of a hook member 8 when the associated door is in closed position, the free end or fore-arm portion of the arm 13 then extending lengthwise of the hook member 8 to the plate end thereof and provided 105 with a downwardly extending pivot stud 14 for fitting into the opening 11 of the socket member 8 with which it is associated. It

is evident that when the door plate 12 is at right angles to the jamb-plate 6 the inner portion of the arm 13 will project away from the associated socket member 8 lengthwise of the jamb-plate 6 and that the fore-arm portion of the arm 13 will project toward the plate 6 at substantially a right angle thereto. When the door is swung outward to open position the inner angled portion of the arm 13 will swing outward around the adjacent free edge of the jamb-plate 6, and when the door has reached a predetermined full open position it will be stopped or prevented from further opening by the outer angled portion of the arm 13 striking at its inner edge against the portion of the plate 6 without the socket 8. When the door hinge member 12, 13 is in full open position it may be disengaged 20 from its socket member 8 by raising it to withdraw the pivot stud 14 from its opening 11, such raising movement of the hinge member being permitted by reason of the space 9 between the upper free end portion 25 of the socket member 8 and the plate 6 being of a width to permit an upward removal of the arm 13 therethrough. The upper arm of the socket member 8 is adapted, however, to overhang the arm 13 when 30 the latter is in any other than full or substantially full open position so that the door member of a hinge can only be placed in or removed from engagement with a socket member 8 when the door member is in substantially full open position.

It is evident that while a single hinge is shown in Fig. 1, two or more hinges may be provided for a set of doors. It will, of course, be understood that after a hinge 40 member 6 has been secured to a body frame the outside casing 4 of the frame is mounted over the hinge to conceal the same from view.

It is apparent that by extending the 45 jamb-plate 6 of a hinge lengthwise of the body instead of crosswise thereof, as is customarily the case, and that by making it of sufficient length to be secured to more than one upright or post 5 of the frame, that 50 it makes a strong and more rigid attachment to the body than would otherwise be the case, and that by utilizing a single body plate in a hanging of two doors, the cost of door hanging is materially lessened and 55 the labor incident thereto reduced from that required where separate hinge members are used for each door.

Another feature of my invention which is of considerable value in connection with the 60 hanging of a door is the vertical adjustability of the socket members 8, the same being bendable to adjust them to stand in a horizontal plane, which is the plane of opening movement of a door, irrespective of the 65 slope or inclination of the portion of the

body to which the hinge plate 6 is secured. With most automobile bodies the sides curve outward and upward so that the plate 6 of a lower hinge stands on an incline when placed against the frame, while the plate of an upper hinge would be in true vertical position or substantially so when placed against the frame, thereby requiring an adjustment of the socket members 8, at least of the lower hinge, to dispose them in proper horizontal position for the hanging of a door.

I wish it understood that my invention is not limited to any specific construction, arrangement or form of the parts as it is capable of embodiment in numerous forms without departing from the spirit of the claims.

Having thus described my invention, what I claim as new and desire to secure by Letters Patent, is,—

1. A hinge of the class described comprising a jamb-plate for attaching to a side of a door jamb, a socket member projecting inwardly from the plate adjacent to the door opening end thereof, with its socket facing and open to the door opening, the socket member having an opening at the top of its plate end and having a pivot receiving hole in its bottom portion below such top opening, and an L-shaped projecting hinge member for attaching to a door edge and having its outer angled end lying in the socket member longitudinally thereof when the projecting member is in closed position, said projecting member having a pivot projecting downward from its free end portion into the hole of the socket member, the projecting member being removable upward from engagement with the socket member through its top opening when swung to a predetermined open position relative to the socket member.

2. The combination with means forming a door opening with a door jamb at a side edge thereof, and a door mounted in the opening, of a hinge plate secured to the outer side of the jamb, a socket member bendably projecting inwardly from the plate adjacent to the door opening end thereof with its socket facing and open to the door opening, the socket member having an opening at the top of its plate end and having a pivot receiving hole in its bottom portion below such top opening, a second plate secured to the inner edge of the door, and an L-shaped projecting member extending from the inner edge portion of the door plate and having its outer angled end lying in the socket member longitudinally thereof when the door is in closed position, said projecting member having a pivot projecting downward from its free end portion into the hole of the socket member, the projecting member being removable upward from en-

gagement with the socket member through its top opening when the door is swung to a predetermined open position.

3. In combination with means forming a door opening with a jamb-post at an edge thereof and a door mounted in the opening, of a hinge comprising a jamb-plate secured to the outer side of the jamb-post and having a hooked member projecting inwardly therefrom to form a socket which is open to and faces the door opening, the terminal of the hooked member being disposed at the upper side of the member in spaced relation to the plate, and the shank portion of the hook having a pivot receiving opening therein adjacent to the plate, the hooked member being capable of vertical angular adjustment with respect to the plate, and an L-shaped projecting member secured to the door edge and projecting therefrom in the plane of the door and then outwardly at substantially a right angle to such plane, and adapted to fit at its outer angled end in the member socket, the free end of the projecting member having a pivot stud projecting therefrom into the socket member hole, the projecting member being removable upward from engagement with the socket member through the space between the plate and free end of the hooked member when the door has been swung to a predetermined open position.

4. The combination with a vehicle body having front and rear door openings in a side thereof with jamb posts at adjacent sides of said openings, and a door mounted in each opening, of a single jamb-plate connecting and secured to the outer sides of the jamb posts and extending at its ends adjacent to the respective door opening, a socket member carried by and projecting inward from the plate adjacent to each end thereof and being open to and facing the adjacent door opening, each socket member having an opening in its top adjacent to the plate and a pivot receiving hole in its bottom portion below the opening, and an L-shaped projecting member secured to the inner edge of each door with its outer fore-arm portion lying in the socket member longitudinally thereof when the door is in closed position and having a pivot stud projecting downwardly from its free end portion into the hole of the socket member, the projecting member being removable from the socket member upwardly through the top opening thereof when the door has been swung open a predetermined extent.

5. The combination with a vehicle body having front and rear door openings in a side thereof with jamb posts at adjacent sides of said opening, and a door mounted in each opening, of a single jamb-plate connecting and secured to the outer sides of the jamb posts and extending at its ends adjacent to the respective door openings, a socket member carried by and projecting inwardly from the plate adjacent to each end thereof and being open to and facing the adjacent door opening, each socket member having an opening in its top adjacent to the plate and having a pivot receiving hole in its bottom portion below the opening, and an L-shaped projecting member secured to the inner edge of each door with its outer fore-arm portion lying in the socket member longitudinally thereof when the door is in closed position and having a pivot stud projecting downwardly from its free end portion into the hole of the socket member, the projecting member being removable from the socket member upwardly through the top opening thereof when the door has been swung open a predetermined extent, the ends of the plate coacting with the projecting member to limit the opening swinging movements of the doors.

6. The combination with a vehicle body having front and rear door openings in a side thereof with jamb posts at adjacent sides of said openings, and a door mounted in each opening, of a single jamb-plate connecting and secured to the outer sides of the jamb posts and extending at its ends adjacent to the respective door openings, a socket member integral with and projecting inward from the plate adjacent to each end thereof and being vertically bendable with respect to the plate, each socket member having an opening in its top adjacent to the plate and having a pivot receiving hole in its bottom portion below the opening, and an L-shaped projecting member secured to the inner edge of each door with its outer fore-arm portion lying in the socket member longitudinally thereof when the door is in closed position and having a pivot stud projecting downwardly from its free end portion into the hole of the socket member, the projecting member being removable from the socket member upwardly through the top opening thereof when the door has been swung open a predetermined extent.

In testimony whereof I have hereunto subscribed my name to this specification.

HARRY N. SÖRENSEN.
